KIDDY SWING

Vernon D. Reid, Sr., Westlake, La.

Application February 4, 1947, Serial No. 726,281

1 Claim. (Cl. 155—65)

1

This invention relates to improvements in swings for use by children.

It is an object of the invention to provide a swing for use especially by small children, which swing has a low center of gravity, a rigid non-upsettable frame, and which can accommodate one to four children at a time.

A further object is the provision of a swing which is actuated by an easy push and pull action of a child's arms and legs.

A further object is to provide a swing which has no springs or chains to replace, and in which there is no danger of being hurt by a moving part of the swing. The seat board is cut away to provide ample space for the legs so that the feet may rest on a foot rest. The swing can be easily moved from place to place as a unit without disassembling, and has braces so placed as to be out of the way of children on the swing.

A further object of the invention is to provide a swing of this type which will be comfortable to sit on and to operate and wherein the child's legs can be disposed close together upon the foot rest and at opposite sides of the seat board and wherein there is provided a wide portion of the board on which the child sits.

These and other objects are attained by the novel construction and arrangement of parts hereinafter described and illustrated by the accompanying drawings, forming a part hereof, and in which:

Fig. 1 is a perspective view of a swing embodying the invention.

Fig. 2 is a diagrammatic view of the swinging action of the device.

Fig. 3 is a plan and side view of the seat of the swing.

Fig. 4 is a perspective view of a push and pull frame on the swing.

Fig. 5 is a perspective view of a seat hanger bar.

Fig. 6 is a perspective view of a movable connecting bar.

Fig. 7 is a view on the line A—A of Fig. 1. Referring to the drawings, the swing is shown in Fig. 1 to comprise a main frame having base bars 1, to which are attached upstanding posts 2, connected to the bars 1 by braces 3. Mounted on the top of each post is a bearing 4, and passing through pairs of bearings are pipes or rods 5, which also rotatably pass through straps 6 on seat hanger bars 7. At each end of seat 8 are two spaced bearings 8', between which are positioned rods 9, journaled in bearings 10 on the hanger bars 7.

2

Passing through bearings 11 on the hanger bars 7, at one end of the swing, is a rod 12 which passes through a bearing 13 on a movable connecting bar 14, which is connected by a bolt 14' passing through its bearing 15 and closely spaced upstanding posts 16, which are connected to foot rest 17 which is connected to widely spaced uprights 18, the latter and the posts 16 being connected to a hand bar 19 which extends above the board 8. The seat board 8 is narrowed to a small dimension at its intermediate portion as indicated at 20 to be disposed between closely spaced posts 16. By having the narrowed intermediate arrangement the children's legs can be comfortably placed on the foot rest piece 17. The portion 20 is reinforced by a narrow board piece 21 connected by bolts thereto. A bearing 23 is connected to the intermediate portion 20. A pin 24 extends through the bearing and closely spaced posts 16. The bars 1 are held spaced apart by transverse pieces 26 connected to the bottom faces of the bars 1 so that they are removed from interference with movable parts of the swing.

It will be seen that the swing has no springs or chains and is sturdy in structure with no parts to fly about to cause injury to a child. The swing is actuated by pulling on the bar 19 and pushing on the foot rest 17 with the legs. Two persons can operate the swing and the seat board 8 is long enough to accommodate two more persons. The swing can be easily moved about without disassembling, and can be conveniently manufactured.

The above description is to be considered as illustrative and not limitative of the invention of which modifications can be made without departing from the spirit and scope of the invention as set forth in the appended claim.

The invention having been described, what is claimed is:

In a swing, a main frame having parallelly disposed base bars, on the outer ends of which are fixed the lower ends of four upstanding posts and braces connecting each post to the base bar 45 to which they are fixed, transverse pieces connected at their outer ends to the outer ends of the base bars to maintain the base bars in spaced relation to each other, a bearing on the top of each post, rods passing through each pair of 50 bearings each rod parallel to one of the transverse pieces so that said rods are supported by said posts, pairs of seat hangers suspended from the rods at the opposite ends of the frame, bearings on said hangers, a rod passing through the 55 bearings on each pair of hangers, a seat in the

form of a board supported on the undersurface thereof by the rods carried by the hangers, bearings positioned over each rod to hold the seat on the rod, a connecting bar pivotally connected to one pair of hangers, a foot rest, a hand bar, second posts connecting the foot rest and hand bar, a cross bolt connected to the connecting bar, and said cross bolt pivotally connected to certain of said second posts, a pin pivotally connecting said last named posts to the center of the seat and said seat board having a narrow intermediate portion whereby said second posts at the opposite sides of the board can be closely spaced together to render the foot rest more comfortable to the

legs of a child on the swing and said swing can be actuated by two children.
